UNITED STATES PATENT OFFICE.

HENRI AUGUSTUS GUILLEY, OF EASTON, PENNSYLVANIA, ASSIGNOR TO INGERSOLL-RAND COMPANY, OF JERSEY CITY, NEW JERSEY, A CORPORATION OF NEW JERSEY.

ROTATION RELEASE FOR ROCK DRILLS.

Application filed October 23, 1920. Serial No. 418,928.

To all whom it may concern:

Be it known that I, HENRI AUGUSTUS GUILLEY, a citizen of the United States, and a resident of Easton, county of Northampton, and State of Pennsylvania, have invented 5 certain new and useful Improvements in Rotation Releases for Rock Drills, of which the following is a specification.

This invention relates to rock drills of the 10 hammer type having automatic rotation for the drill steel, as for instance rifle bar rotation, but relates more particularly to a device for releasing the rotation when desired.

The primary object of the invention is to 15 enable the operator to change from a positive or substantially positive rotation to a slip rotation at will, as for instance in hard ground.

If the drill steel sticks, it may be desirable 20 to release the positive rotation and permit the hammer to operate with slip rotation or operate without rotating the drill steel, until the normal rotation can be resumed, and my rotation releasing device 25 accomplishes these objects in a simple and efficient manner and without complication of parts.

To these ends the invention is shown in 30 one of its preferred forms in the accompanying drawings, in which—

Figure 1 is a longitudinal sectional elevation 35 of a portion of a rock drill containing the device, and taken on the line 1—1 of Figure 2, looking in the direction of the arrows,

Figure 2 is a transverse sectional elevation taken on the line 2—2 of Figure 1, and

Figure 3 is a detail sectional view of a 40 modification of the brake adjusting mechanism.

In order to illustrate the invention, a fluid 45 pressure actuated rock drill of the hammer type having a rifle bar rotation is illustrated, only so much of the machine and its operative parts being shown as will serve to make the invention clear, the complete showing of the ports and passages for the supply of motive fluid to the hammer cylinder being omitted as forming no part of 50 the present invention.

Referring to the drawings, the hammer piston A which may be of any suitable or usual construction, is adapted to reciprocate in the cylinder B and is actuated by fluid pressure supplied and distributed in any 55 suitable manner.

The piston A or its rearward extension is hollow and engages the rifle bar C having a head D located between the rotation washer E and the back head F of the machine. The rifle bar head is provided with a gudgeon G having a bearing in the back head F and in the form of construction shown, a strong cushion spring H, preferably a leaf spring, bears against the back head F and through bolts J passing through the cushion spring H and lugs K on the cylinder in the usual manner hold the parts together.

The rifle bar head D is provided with 70 the rotation pawls L adapted to engage the teeth of the rotation ratchet ring O, which surrounds the head D and is adapted to be held from rotation by means of the rotation releasing device forming the principal 75 subject matter of this invention and shown as a brake band P substantially encircling the periphery of the rotation ratchet ring O.

Means are provided for tightening and 80 loosening the brake band in order to change from substantially positive to slip rotation and in this instance, a bolt Q extends transversely through the cylinder B adjacent the rotation ratchet ring, so that the shank R of the bolt lies in a chamber S formed in the cylinder. The inner end of the bolt has a bearing at T in the cylinder and the head U of the bolt is provided with a packing gland and the lock nuts W and X. The shank R of the bolt passes through one end Y of the 85 brake band P and also passes through the apertures a and b in the other reversely bent end Z of the brake band. In order to hold the end Z of the brake band tightly on the bolt, said end preferably encloses a nut c 90 on the screw threaded portion d of the shank of the bolt.

By loosening the lock nuts W and X and turning the bolt Q in one direction or the other, the nut c will travel along the screw 100

threaded portion *d* of the bolt in a direction to tighten or loosen the brake band as desired, and either provides positive or substantially positive rotation for a drill steel 5 or slip rotation for a drill steel. After the rotation has been adjusted as desired, the lock nuts *W* and *X* are tightened and should remain tightened during the operation of the machine.

10. The packing gland *V* makes a tight joint around the head *U* of the bolt *Q* and in order to avoid loss of pressure by leakage in the construction, a seal is made at the periphery of the inner face *e* of the back head *F* and 15 this may conveniently be done by counterboring the back end of the cylinder into which counterbore the back head *F* is fitted for a portion of its thickness. Any fluid pressure which may enter the space between the 20 rotation washer *E* and the back head *F* due to the working clearance between the parts of the rotation device, cannot escape due to the seal at the point *e* and the sealing of the bolt *Q* around the stud head *U*.

25. In Figure 3 a modification of the brake adjusting mechanism is shown designed to more effectually withstand vibration and insure the sealing of the brake bolt without the use of packing.

30. In Figure 3, the brake bolt *Q'* is provided with a collar *U'* adapted to be seated firmly against the bottom *f* of the recess or socket *g* in the side of the cylinder *B'*. The joint between the meeting surfaces at the bottom 35 of the socket *g* and the inner face of the collar *U'* should preferably be a machined joint, which seals the bolt without the requirement of packing at this point. A screw plug *h* having a head *j* forces the collar *U'* tightly 40 against the bottom of the socket and the parts are locked in position by means of a

suitable lock nut *k* outside of the plug *h*. In this modification the head *o* of the adjustable brake bolt is preferably squared for adjusting purposes.

I claim:

1. A rock drill of the hammer type having positive automatic rotation for a drill steel including a cylinder, a ratchet ring, a brake band cooperating with said ratchet ring and located within the cylinder, a longitudinally immovable bolt, passing through the wall of the cylinder and both ends of said band, a nut on said bolt, one end of said band being secured on the bolt and the other end being adapted to be moved in either direction by engagement with said nut for tightening and loosening said brake to change from substantially positive to slip rotation and external screw threaded means for positively securing said bolt in adjusted position, said means including a fluid-tight seal for preventing leakage past said bolt. 55

2. A rock drill of the hammer type having positive automatic rotation for a drill steel including a cylinder, a ratchet ring, a brake band cooperating with said ratchet ring and located within the cylinder, a bolt passing through the cylinder and both ends of said band, a nut on said bolt, one end of said band being secured on the bolt against relative movement and the other end being reversely bent on the bolt and enclosing said nut, said reversely bent end being adapted to be moved in either direction by engagement with said nut for tightening and loosening said brake to change from substantially positive to slip rotation. 75

In testimony whereof I have signed this specification. 80

HENRI AUGUSTUS GUILEY.
